UNITED STATES PATENT OFFICE.

SARA MYERS, OF GLOVERSVILLE, NEW YORK.

DESIGN FOR A SLIPPER ORNAMENT.

Application filed April 19, 1926. Serial No. 17,343. Term of patent 7 years.

To all whom it may concern:

Be it known that I, SARA MYERS, a citizen of the United States, and a resident of Gloversville, in the county of Fulton and State of New York, have invented a new, original, and ornamental Design for Slipper Ornaments, of which the following is a specification, reference being had to the accompanying drawings, forming part thereof.

I claim:

The ornamental design for a slipper ornament, as shown.

SARA MYERS.
